ASSIGNORS TO STANDARD OIL COMPANY, OF WHITING, INDIANA, A CORPORATION
OF INDIANA.

MANUFACTURE OF LEAD ALKYL COMPOUNDS.

No Drawing.

Application filed October 6, 1924. Serial No. 742,063.

The present invention relates to improvements in the manufacture of lead alkyl compounds, and more particularly of lead tetraethyl, and will be fully understood from the following description thereof.

The invention will be specifically described in connection with the manufacture of lead tetraethyl, although, as hereinafter pointed out, other lead alkyl compounds may be manufactured under the process of this invention.

In carrying out the invention for the formation of lead tetraethyl, a sodium lead alloy is subjected to the action of ethyl sulfate, preferably in the presence of a halogen containing compound, preferably an inorganic halide. The sodium lead alloy may contain from 3 to 31% of sodium, it being preferred that its sodium contents be within the range of from 5 to 20%. The alloy containing 10% of sodium has been found to be particularly suitable. The amount of diethyl sulfate employed is preferably not in excess of the calculated equivalent required for reaction with the lead alloy, only one ethyl group being considered as reactive. Thus for 100 parts of sodium lead alloy containing 10% of sodium, the calculated equivalent quantity of diethyl sulfate is about 67 parts. The use of 50 parts has been found to be particularly advantageous, although lower or higher proportions may be employed. It is not generally desirable that the proportion of diethyl sulfate employed be less than 50% of the calculated equivalent. A non-aqueous solvent such as benzol, toluol or the like may be employed, serving primarily to control the rate of reaction. It is also desirable that a slight trace of water be present.

The reaction constituents are admixed, preferably with the solvent, the proportion of which, when used, may vary from an amount equal in weight to the amount of ethyl sulfate to from 50 to 100% more, and a trace of water, say two to three drops may be added. The entire mixture is then heated to boiling under a reflux condenser or may be heated under pressure while being stirred until reaction is completed to the desired extent.

It is preferred that a small amount of a halogen catalyst be added. Thus chlorine,

bromine, iodine, or their salts, such as the alkali metal, alkaline earth metal, and zinc halides and the like may be employed. The proportion required is very small, in general from one-half to three per cent based on the diethyl sulfate content of the mixture being sufficient. With potassium iodide as a catalyst, highly satisfactory results have been obtained employing 1%.

The following specific instance of a process carried out under this invention illustrates satisfactory conditions for operation.

100 parts of sodium lead alloy containing 10% of sodium, 50 parts of ethyl sulfate and about 65 parts of toluol are thoroughly mixed, 0.5 parts potassium iodide and a trace of water (two or three drops) being added. The mixture is boiled under a reflux column while being stirred, the heating being continued until the reaction is carried to substantial completion, from 4 to 6 hours being required. In order to separate the lead tetraethyl produced, the reaction mixture is treated with water, and distilled or the lead tetraethyl otherwise removed therefrom. The separation may be effected by steam or vacuum distillation, by extraction with ether or other suitable solvent and by other known methods. 20.7 parts of lead tetraethyl, a yield of approximately 80% of theoretical, are obtained.

The presence of a halide catalyst, of which potassium iodide is an example, appears to greatly accelerate the rate of reaction and increase the yield. The reaction may be carried out, however, without such a catalyst, as herein-before stated. The halogens themselves, as chlorin, bromin, and iodin, may be employed if desired, as well as halogen salts.

The invention may be employed in manufacturing other lead alkyl compounds, substituting for the diethyl sulfate other alkyl sulfates, such as dimethyl sulfate, dipropyl sulfate, ethylmethyl sulfate, ethyl propyl sulfate, dibutyl sulfate and the like, the proportion of the various constituents of the reaction mixture being varied as indicated above in connection with the manufacture of lead tetraethyl.

We claim:

1. The method of manufacturing lead alkyl compounds comprising the intermix-

ture of a sodium lead alloy and a dialkyl sulfate, and the subsequent heating of the mixture.

2. The method of forming lead alkyl compounds comprising admixing a sodium lead alloy and a dialkyl sulfate in the presence of a halogen compound derived from the group including the elemental halogens and the soluble metallic halides and heating the mixture.

3. The method of forming a lead alkyl comprising admixing a sodium lead alloy and a dialkyl sulfate in the presence of a halogen compound derived from the group including the elemental halogens and the soluble metallic halides and a trace of water, and heating the mixture.

4. The method of forming lead tetraethyl comprising admixing and heating together a sodium lead alloy and diethyl sulfate.

5. The method of forming lead tetraethyl comprising admixing a sodium lead alloy and diethyl sulfate in the presence of a halogen compound derived from the group including the elemental halogens and the soluble metallic halides and heating the mixture.

6. The method of forming lead tetraethyl comprising admixing a sodium lead alloy and diethyl sulfate in the presence of an iodine compound derived from the group including iodine and the soluble metallic iodides and a trace of water and heating the mixture.

35. 7. The method of forming lead tetraethyl comprising admixing a sodium lead alloy

with diethyl sulfate in the presence of an anhydrous solvent and a halogen catalyst derived from the group including the elemental halogens and the soluble metallic halides, and heating the mixture.

8. The method of forming lead tetraethyl comprising admixing a sodium lead alloy with diethyl sulfate in amounts not in excess of the monomolecular equivalent, incorporating in the mixture a halogen catalyst derived from the group including the elemental halogens and the soluble metallic halides and heating the mixture.

9. The method of forming lead tetraethyl comprising admixing a sodium lead alloy containing 3 to 31% of sodium with at least 50% of the monomolecular equivalent of diethyl sulfate and heating the mixture.

10. The method of forming lead tetraethyl comprising admixing a sodium lead alloy containing 3 to 31% of sodium with at least 50% of the monomolecular equivalent of diethyl sulfate in the presence of a halogen body derived from the group including the elemental halogens and the soluble metallic halides and a trace of water, and heating the mixture.

11. The method of forming lead tetraethyl comprising admixing 100 parts of a sodium lead alloy containing 10% of sodium, 50 parts of diethyl sulfate, 1/2 part of potassium iodide, about 65 parts of toluol and a trace of water and heating the mixture under a reflux condenser.
